CLAIM

The ornamental design for a resolution enhancer for a surgical microscope, as shown and described.

DESCRIPTION

FIG. 1 is a front perspective view of the resolution enhancer for a surgical microscope of our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left-side elevation view thereof; and,

FIG. 8 is a right-side elevation view thereof.

The broken lines in the drawings are included for the purpose of illustrating unclaimed portions of the resolution enhancer for a surgical microscope and form no part of the claimed design.

1 Claim, 8 Drawing Sheets
